CLAIM

The ornamental design for a microwave converging lens wok, as shown and described.

DESCRIPTION

FIG. 1 is a perspective view of a microwave converging lens wok showing my new design;

FIG. 2 is an exploded perspective view thereof;

FIG. 3 is a front elevational view with all sides being a mirror image thereof;

FIG. 4 is a top view thereof; and,

FIG. 5 is a bottom view thereof.

The broken line showing of handles in FIGS. 1, 3, and 5 is for illustrative purposes only and forms no part of the claimed design.
